UNITED STATES PATENT OFFICE.

OTTO S. BEYER, OF CARLSTADT, NEW JERSEY, ASSIGNOR TO E. W. BLISS COMPANY, OF BROOKLYN, NEW YORK, A CORPORATION OF WEST VIRGINIA.

DRAWING-PRESS.

SPECIFICATION forming part of Letters Patent No. 739,379, dated September 22, 1903.

Application filed August 18, 1902. Serial No. 120,042. (No model.)

To all whom it may concern:

Be it known that I, OTTO S. BEYER, a citizen of the United States, residing at Carlstadt, in the county of Bergen and State of New Jersey, have invented certain new and useful Improvements in Drawing-Presses, of which the following is a specification.

This invention relates to power-presses applicable wherever a plunger having a somewhat long stroke coacts with a bed for supporting the work upon which the plunger operates. Such presses are commonly used for drawing deep sheet-metal cups or sheet-metal tubes or like articles, although applicable for other purposes. As heretofore constructed such presses have commonly had a stationary bed and a plunger coating therewith and having a stroke somewhat in excess of twice the length of the object to be drawn or otherwise operated upon. For example, for drawing a shell or tube to a length of sixteen inches the stroke of the punch must exceed thirty-two inches and to afford proper clearance is ordinarily of as much as thirty-six inches. In such presses the plunger commonly is given a slow working stroke and a somewhat more rapid return stroke, the working stroke being practically limited on ordinarily heavy work to a speed of four to five feet per minute, while the upstroke is made at a speed of from seven to ten feet per minute. Such presses are slow in operation by reason of the long stroke of the punch, more than half of which is performed idly before the punch encounters the work and begins to operate upon it.

My present invention aims to increase the speed of presses of this character, and to this end substitutes for the stationary bed heretofore used a movable bed which upon having the blank placed in position upon the die rises rapidly to carry the work up to the punch or, in other words, to enter the punch within the blank preparatory to the drawing operation. This movement takes place during the beginning of the downstroke of the punch and is completed so that the bed comes to rest and serves as a firm support for the blank just before the punch encounters the latter and begins to draw it through the die. The bed remains stationary during the

drawing movement and then rapidly descends while the punch is ascending. The bed then remains stationary in its lowest position for a time sufficient to enable the operator to feed on a new blank, the punch moving sufficiently higher than the top of the blank to provide not only sufficient clearance, but also to give time enough to the operator to perform the feeding-on operation. The rising and falling movements of the bed may be variously imparted to it; but preferably, since in presses of this kind the punch-carrying plunger is commonly driven by a rack-and-pinion movement reversed at each end of the stroke by a belt-shifter, the bed is driven by independent mechanism which is started and stopped by tappet devices or analogous means, so that the movement of the plunger shall control the movements of the bed so as to properly time the latter with respect to the former.

The general nature of my invention being now understood, I will proceed to describe in detail one embodiment thereof with reference to the accompanying drawings, wherein—

Figure 1 is a side elevation, partly in vertical section. Fig. 2 is a front elevation. Fig. 3 is a sectional view corresponding to the lower part of Fig. 1, showing the parts in a different position. Fig. 4 is a vertical section on the lines 4-4 in Fig. 3. Fig. 5 is a fragmentary view showing the parts at the left in Fig. 3 in one position, and Fig. 6 is a similar view showing the same parts in the opposite position. Fig. 7 is a diagram showing the relative movements of the punch and bed. Fig. 8 is a fragmentary side elevation showing the addition to Fig. 1 of the tappet belt-shifting mechanism.

Referring to the drawings, let A designate an upright frame of any suitable construction for properly supporting the working parts, this frame being shown as comprising upright side pieces A¹ A¹, a fixed base A², and a top cross-piece A³. The frame A is provided with slideways a a, serving as guides for the plunger B, which is shown as a slide working between these slideways. This slide or plunger B carries the punch C, the shape and dimensions of which vary according to the work to be done. The die D, with which

the punch coacts, is mounted on a bed E, which is constructed as a slide to reciprocate vertically between the side frames A', which latter are formed with suitable slideways for 5 properly guiding it.

The plunger B is shown as operated by a rack and pinion, a rack *b* being carried on its rear face, which is engaged by a pinion *c*, fixed on a transverse shaft F. In the construction shown power is applied to drive the shaft F first in one direction and then in the other by means of a suitable system of belts and shifting mechanism. A shaft G has 10 fixed on it a pinion *d*, which drives a gear *e*, fixed on a shaft H, on which is fixed a pinion *f*, which meshes with a gear-wheel *g* on a shaft I, on which is fixed a pinion *h*, meshing with a gear-wheel *i*, fixed on the pinion-shaft F. The pitch-lines of these several gears are 15 shown in Fig. 1.

The bed E is raised and lowered by any suitable mechanism, toggle-joints being shown—that is to say, toggle-links J J are pivoted at their upper ends to the head E on 20 pivot-pins *j* *j*, and the lower ends of these links are engaged by crank-studs *k* on crank-arms K K, formed on shafts L L, which shafts are adapted to oscillate through a half-turn in order that in one extreme position their 25 cranks K K shall be turned downwardly in line with the links, as indicated in Figs. 3 and 4, while in the opposite position they shall be turned upwardly in line with said links, as shown in Figs. 1 and 2.

30 For imparting the requisite half-turns to the shafts L L at proper times I provide a driving-shaft M, which may be driven from any source of power, but is shown as driven from the shaft G by a belt *l* on fixed pulleys *m* *m'*, but which may be thrown onto loose pulleys *o* *o'*. The shaft M is thus driven in one direction or the other, according to the direction in which the shaft G is turning, or by throwing the belt onto the loose pulleys 35 the shaft M is undriven to leave the bed E stationary. On the shaft M is fixed a pinion *p*, meshing with a gear *p'* on a shaft N, on which is fixed a pinion *q*, which meshes with a large gear-wheel P and which in turn 40 drives a like gear-wheel P'. The gears P and P' serve to turn the shafts L L and might be fixed thereon, so as to communicate motion thereto directly; but for the reason hereinafter explained I prefer to mount them 45 loosely on the shafts L L to cause them to drive these shafts through links, whereby to give a variable motion. On the inner face of each gear-wheel P P' is a stud *r*, which is connected by two links *s* and *t* to the crank-50 stud *u* on a crank-arm L', fixed on the shaft L. The links *s* *t* are jointed together by a pin *s'*, which carries a roller *t'*, which roller rolls in a cam-groove *v*, formed in a stationary cam-plate Q. The active portions of the 55 cam-grooves *v* are concentric with the shafts L, so that the thrust transmitted by the studs *r* to the links *s* *t* is communicated to the crank-

stud *u* in the same manner as though a single link were interposed between the studs *r* and *u*, and consequently the shafts L L are 70 caused to turn coincidently with the gear-wheels P P'. These concentric portions of the cam-grooves *v* continue for one hundred and eighty degrees or sufficiently to cause the rotation of the gear-wheels P P' to communicate a half-rotation to the shafts L L, so as to carry their cranks from the bottom dead-center to the top dead-center, or vice versa, and thereby communicate the complete rising and falling movement to the bed. If the 75 gear-wheels P P' were driven by positively acting mechanism, so as to be started and stopped at precisely the correct time and without lost motion due to inertia caused by the starting and stopping of the parts 80 connected with the bed, these gear-wheels might be fixedly attached to the shafts L L; but as these conditions are not practically attainable without serious disadvantages and as it is desirable to drive the bed-operating 85 mechanism through a belt and to start and stop it by a belt-shifter it is necessary to make provision for a varying amount of irregularity in the time occupied in starting and stopping the moving parts. Accordingly 90 I provide for giving the gear-wheels P P' an extra or excessive movement beyond the requisite one hundred and eighty degrees and for taking up this excessive movement, so that it shall not be communicated to the 95 shafts L L. To this end the cam-groove *v* is provided with idle extensions or branch grooves *v'* *v''* at its opposite ends, so that the movement of the wheel P or P' may not be communicated to the shaft L, but instead will 100 be taken up by an idle travel of the roller *t'* into one or the other of these extensions *v'* *v''*. In order that this idle travel may not affect the shaft L, the groove extensions *v'* *v''* are made concentric with the center of the crank-stud *u* 105 when the latter is in either extreme position—that is to say, the lower extension *v'* is, as shown in the diagram Fig. 5, concentric with the crank-stud *u* when the bed is lowered, while the extension *v''* is, as shown in the diagram Fig. 6, concentric with the center of the 110 crank-stud *u* when the bed is elevated. In Figs. 5 and 6 it is apparent that the driving-stud *r* may move between the positions marked *r'* and *r''* without imparting any motion to the 115 shaft L, because this movement simply causes the roller *t'* to travel in the slot extension *v'* or *v''*, during which the link *t* merely swings around the center of the stud *u* without displacing the latter. Hence the wheels P P' may 120 be given any extra or idle movement beyond the one hundred and eighty degrees movement necessary to actuate the bed within the limit imposed by the length of the groove extensions *v'* *v''*—that is to say, the wheels may 125 have an angular movement not exceeding that from *r'* to *r''*—and within these limits this idle movement varies greatly. The margin 130 thus allowed is ample to provide for any va-

riation due to slip of the belts or to the effect of variations in the tightness of the belting upon the starting or stopping of the parts. It also in the case of a tappet-actuated belt-shifter permits of some inaccuracy in the adjustment of the tappets and obviates the necessity of an extremely nice adjustment.

The relative movements of the plunger and bed are indicated by the diagram Fig. 7, where 10 the zigzag lines R R' indicate the slow descending and more rapid ascending movements of the plunger, while the line S indicates the movements of the bed. Starting at 1 the plunger is at top stroke while the bed has been resting in its lowermost position. At this instant the bed-operating mechanism is set in motion and the bed ascends until the plunger has descended to the point 15 2, coming to rest in its uppermost position just before the punch encounters the die at 3, whereupon the bed remains at rest during the entire drawing operation, the duration of which is indicated by the arrow 4, and the depth of draw is indicated by the arrow 5. 20 As soon as the plunger reaches the bottom of its stroke the direction of motion of its driving-shaft G is reversed and it begins to ascend according to the line R', while at the same instant—namely, point 6—the bed-driving mechanism is set in motion and the bed descends during the first portion of the ascent of the plunger and until the point 7, whereupon the bed remains down at rest during the remainder of the upstroke of the plunger (during which time the operator feeds on 25 a new blank) and until the plunger has recommenced its downstroke, whereupon the bed again rises, and so on. It will be observed that for a given depth of blank the stroke necessary for the punch is shortened by exactly the amount of lift imparted to the bed. Thus the press is made much more compact than any rack-and-pinion press heretofore made. It will be understood that the 30 drawn blank is separated or stripped from the punch in any known manner—that is to say, either by delivering it out from the die, so that it falls through the bed before the latter descends, or, if preferred, by carrying it up on the punch and then stripping it therefrom, so that the operator removes it from above the die before replacing it with a new blank.

Although the specific means for reversing the movement of the shaft G and of shifting the belt for driving the shaft M are not essential to my invention, I will, to enable the application of my invention to be understood, briefly describe such mechanisms. 35 The main shaft G may be driven from any suitable continuously-rotating shaft, as the shaft 11 in Fig. 2, the connection being made through any suitable reverse drive mechanism, such as a pulley 12, carrying a direct belt 13 and a cross-belt 14, either of which belts may be thrown upon a pulley 15, which is fixed upon the shaft G, loose pulleys 16 and

17 being provided for carrying the belts when thrown off from this fast pulley. The belts are shifted by a belt-shifter 18, consisting of a slide carried in suitable bearings and adapted to be thrown in one direction or the other as the clutch-carrying slide or plunger reaches the top or bottom of its stroke. For this purpose any suitable tappet mechanism may be provided. I have shown the slide B carrying two tappets 19 and 20, which are vertically adjustable in a slot 21. When the slide in ascending approaches the upper limit of its stroke, its tappet 19 strikes a roller 22, carried on an elbow-lever 23, fixed on a shaft 24, thereby tilting this lever to the position shown in Fig. 2, whereby movement is communicated to an arm 25, fixed on the opposite end of the shaft, 75 Fig. 8, which carries at its lower end a pin 26, which enters a slot in a long lever 27, which is pivoted at 28, and the free lower end of which is provided with a slot engaging a pin 29 on the slide 18, whereby to move the slide 80 to the position shown in Fig. 2. When the punch-carrying slide B approaches the lower end of its stroke, its other tappet 20 strikes a roller 30, carried in a different plane on another arm of the lever 23, and tilts this lever 95 in the contrary direction, thereby swinging the lever 27 over to the position indicated in dotted lines in Fig. 2 and displacing the slide 18, and consequently the belts, to the extreme position to the left, whereby the direct belt 13, which until this instant has been driving the shaft G, is run off the fast pulley 15, and the cross-belt 14 is thrown onto this pulley, whereby the shaft G is driven in the contrary direction, and through the intervening gearing described the slide B is caused to ascend.

For shifting the belt 1, I provide a belt-shifter 31, which may be a slide by which the belt may be thrown onto the fast pulleys *m* 110 or loose pulleys *o* *o'*, and I provide suitable tappet mechanism for operating this shifter. I have shown a tappet 32 carried by the slide B by means of brackets 53 53, in which it is adjustable, as by being screw-threaded or otherwise. When the slide B descends to nearly the bottom limit of its stroke, it strikes a lever-arm 33 on a shaft 34, from which projects an arm 35, which arms 33 35 constitute a lever which is tilted upward 115 from the position shown in Fig. 2, and in so doing the arm 35, which engages the collars on a rod 36, lifts this rod, and thereby communicates motion through a bell-crank 37 to the belt-shifter 31, which it thereby throws 120 to the left to carry the belt onto the fast pulleys. The belt is shifted at about the same instant that the motion of the shaft G is reversed, whereupon as the shaft G is turning in the direction for causing the punch to ascend motion is communicated through the belt 1 to cause the bed E to descend. When the bed reaches the limit of its downward stroke, a tappet projection 38, carried by it,

strikes a pivoted cam 39, carried on the belt-shifter slide 31, and thereby the belt is thrown back onto the loose pulley, so that the movement of the bed is stopped by the time that 5 the projection 38 has passed below the cam 39, and the bed then remains stationary during the remainder of the ascent of the punch. When the slide B nears the upper end of its stroke, any suitable tappet upon the slide en- 10 gages in any suitable manner means for again throwing the belt-shifter 31 to carry the belt from the loose to the fast pulleys. For this purpose I have shown a vertically-adjustable tappet 40, Fig. 2, which strikes the end of a 15 lever 41, Fig. 8, the rearward arm of which on the opposite side of its fulcrum connects with a tappet-rod 42, which passes down at the rear of the machine, and when depressed by this movement its lower end strikes an 20 arm 43 on the shaft 34 (which arm is a duplicate of the arm 33) and again oscillates this shaft exactly as did the tappet 32 in striking the arm 33, thereby through the arm 35, rod 36, and elbow-lever 37 the belt-shifter is 25 again operated to throw the belt onto the fast pulleys, so that the bed is caused to rapidly ascend as the punch begins its descent. When the bed has ascended to its upper position, a tappet-dog 44, carried by the bed, en- 30 counters an arm 45, fixed on the shaft 34, and rocks this shaft to the position shown in Fig. 2, thereby again moving the bed-shifter to throw the belt onto the loose pulleys.

With the type of drawing-press to which 35 my invention is applied, as shown in the drawings, it is not customary to use a blank-holder. My invention, however, does not exclude the use of a blank-holder.

It must not be inferred from the particu- 40 larity of detail with which I have described my invention that I am necessarily limited to the details set forth, as my invention may be greatly modified in matters of mechanical detail without departing from its essential fea- 45 tures.

What I claim is—

1. In a drawing-press, the combination of a punch-operating plunger, a reversible driving mechanism for reciprocating it, means for 45 mechanically reversing such mechanism at each movement of the punch, a die-supporting bed movable toward and from the plunger, and mechanism adapted to move said bed toward the plunger, hold it stationary during the draw, and retract it from the plunger after the draw.

2. In a drawing-press, the combination of a punch-operating plunger, a reversible rack-and-pinion mechanism for reciprocating it, a 50 die-supporting bed movable toward and from the plunger, and mechanism adapted to move said bed toward the plunger, hold it stationary during the draw, and retract it from the plunger after the draw.

3. In a drawing-press, the combination of a punch-operating plunger, a reversible driving mechanism for reciprocating it, means for

mechanically reversing such mechanism at each movement of the punch, a die-supporting bed movable toward and from the plunger, and mechanism driven from said reversible driving mechanism, and adapted to move said bed toward the plunger, hold it stationary during the draw, and retract it from the plunger after the draw. 70

4. In a drawing-press, the combination of a punch-operating plunger, a reversible driving mechanism for reciprocating it, a die-supporting bed movable toward and from the plunger, and tappet-controlled mechanism 80 driven from said reversible driving mechanism, and adapted to move said bed toward the plunger, hold it stationary during the draw, and retract it from the plunger after the draw. 75

5. In a drawing-press, the combination of a punch-operating plunger, a die-supporting bed movable toward and from the plunger, a reversible operating-shaft geared to said plunger, means for reversing the rotation of said shaft at the end of each stroke of the 90 plunger, mechanism for moving said bed, and means for connecting said mechanism to said operating-shaft to start the movements of the bed and disconnecting it therefrom to stop the bed. 95

6. In a drawing-press, the combination of a punch-operating plunger, a die-supporting bed movable toward and from the plunger, a reversible operating-shaft geared to said plunger, means for reversing the rotation of 100 said shaft at the end of each stroke of the plunger, mechanism for moving said bed driven from said operating-shaft, tappets controlled by the plunger for coupling said mechanism to said shaft to start the movement of 105 the bed, and tappets controlled by the bed for uncoupling said mechanism from said shaft to stop the movements of the bed.

7. In a drawing-press for deep drawing, the combination with a punch-operating plunger 110 having a stroke less than double the length of the maximum draw, of a die-supporting bed movable toward and from said plunger with a stroke approximately equal to the maximum draw, and mechanism adapted to move said 115 bed rapidly (relatively to the speed of the plunger) toward the plunger to cause the punch to enter the blank, hold it stationary during the draw, and retract it from the plunger immediately after the draw, whereby the 120 stroke of the plunger is shortened by an amount approximating the length of draw.

8. In a drawing-press, the combination with a plunger, a movable member coacting therewith, and mechanism for driving said member liable to a variable movement beyond that necessary to produce the required movement of said member, of means interposed between such mechanism and said member for neutralizing such variable excessive movements, so that they are not communicated to the latter. 125

9. In a drawing-press, the combination with a plunger, a movable member coacting there-

with, a shaft adapted by a determined partial revolution to move said member from one of its positions to the other, and driving mechanism for imparting to said shaft such

5 partial revolutions, said mechanism liable to a variable movement beyond that necessary to produce the required movement of said shaft, of means for taking up such variable excessive movements without communicating

10 them to said shaft.

10. In a drawing-press, the combination of a reciprocating punch-operating plunger, a die-supporting bed, toggle mechanism adapted to raise and lower said bed comprising a 15 crank-shaft and toggle-links, connecting its cranks with the bed, a reversible driving mechanism adapted to communicate alternate half-revolutions to said shaft, said driving mechanism liable to a variable movement 20 beyond that necessary to produce said half-revolutions of said shaft, and means for taking up such variable excessive movements, whereby to avoid communicating them to said shaft and thence to the bed.

25 11. In a drawing-press, the combination of a reciprocating plunger, an intermittently-movable bed, mechanism for moving said bed comprising an oscillating shaft connected to said bed, an oscillating part for driving said 30 shaft, said part being liable to a variable movement beyond that necessary to produce the required movement of said shaft, and

take-up mechanism for communicating the movement of said oscillating part to said shaft comprising a roller connected to said parts respectively, and a guiding-groove for said roller having an active portion corresponding to the movement transmitted to said shaft, and inactive portions in which said roller may travel idly during such variable excessive movements.

12. In a drawing-press, the combination of a reciprocating plunger, an intermittently-movable bed, mechanism for moving said bed comprising an oscillating shaft connected to said bed, an oscillating part for driving said shaft, and take-up mechanism for communicating the movement of said oscillating part to said shaft comprising links connecting a stud on said part to an arm on said shaft, a 45 roller at the junction of said links, and a guiding-groove for said roller having an active portion concentric with said shaft, and inactive portions adapted to permit the roller to play freely around the terminal positions 50 of said arm.

In witness whereof I have hereunto signed my name in the presence of two subscribing witnesses.

OTTO S. BEYER.
